FIG. 1

FIG. 2

3 4

FIG. 4

FIG. 3

FIGURE 1 is a top plan view of a package for fruit or the like showing my new design;

FIGURE 2 is a front elevation, partly broken away and in section;

FIGURE 3 is a sectional view along the line 3—3 of FIGURE 2; and

FIGURE 4 is an end elevation in section along the line 4—4 of FIGURE 2.

The dominant features of my design reside in the combination on the package shown of the longitudinally-ribbed chamber dividers and asymmetrical chambers wherein

the tops are hemispheric and the bottoms are truncated cones terminating in rounded bases with indented centers.

I claim:

The ornamental design for a package for fruit or the like, as shown and described.
